UNITED STATES PATENT OFFICE.

RUSSELL I. RHODES, OF NORTH ATTLEBORO, MASSACHUSETTS.

JEWELRY-BOX HINGE.

Application filed November 25, 1924. Serial No. 752,175.

To all whom it may concern:

Be it known that I, RUSSELL I. RHODES, a citizen of the United States of America, and resident of North Attleboro, in the 5 county of Bristol and State of Massachusetts, have invented new and useful Improvements in Jewelry-Box Hinges, of which the following is a specification.

This invention relates to hinges for boxes 10 or cases such for example as jewelry boxes and objects of the invention are to provide a simple, durable and reliable hinge having the new and improved features of construction and arrangement hereinafter described.

15 The invention is illustrated in one of its preferred forms in the accompanying drawings in which

Fig. 1 is a perspective of a jewelry box embodying the invention;

20 Fig. 2 is a perspective of one of the hinge straps; and

Fig. 3 is a perspective of the spring.

In the embodiment of the invention illustrated the jewelry box which may be of cardboard or other suitable material comprises a bottom or body portion 1 to which the cover or lid 2 is connected by means of a hinge A which consists of upper and lower hinge members connected to the cover and body of 25 the box respectively. The hinge members are similarly constructed and each comprises a base plate 3 of sheet metal or other suitable material connected to the box structure by extruded or struck-out prongs 4 which extend through and are bent over the cover or bottom of the box as indicated, a portion of the plate being cut out as at 5^a to reduce the weight thereof to a minimum. It will be observed that the plates 3 extend a substantial 30 distance across the box toward the opposite end thereof so that in this manner the strength of the box is materially enhanced and frequent opening and closing will not operate to tear the hinge from the box, it being understood that ordinarily these boxes 35 are constructed of comparatively easily tearable material which is not adapted to withstand excessive abuse.

Integral with the plate 3 and extending at 40 substantially right angles therefrom is a leaf 5 of approximately the same width as that of the adjacent box wall and connected to the leaves 5 are a pair of hinge straps 6 and 7. Flexible metal clamps 8 extend through the 45 walls of the box, apertures in the leaves and apertures 9 in the straps registering there-

with for securely fastening the several parts together. Each strap is formed with integral tabs or knuckles 10 arranged to intermesh with each other and which are bent 60 around a pin thereby hingedly to connect the straps.

Formed on the free longitudinal edge of each of the hinge straps 6 as by stamping is an integral outwardly curved lip 11 which 65 is preferably located centrally between the ends of the strap. Attached to the integral lips 11 are hooked end portions 12 of a leaf spring 13 of spring metal, which serves to hold the box in open or closed position as 70 hereinafter described. The lips 11 enable the spring 13 to be readily and conveniently attached to or detached from the hinge without the inconvenience of disassembling the hinge structure. Owing to the extreme 75 simplicity of construction the straps may be manufactured at a minimum cost, and as assembled a hinge is produced which is sturdy, durable and has no parts which are liable to break or get out of order. The 80 single leaf spring is of decided advantage because of its convenient assembly with the hinge structure and its sturdiness and reliability as well as its simplicity.

It will readily be understood that when 85 the hinge members are rotated about the pivot from the position in which the box is open to closed position the hooked ends of the spring bear against the straps 6 bending the body of the spring and also forcing the 90 hooks farther apart. Thus it may be said that two forces are exerted on the hinge by the spring, one a bending movement due to the bending of the body whereby the ends exert a bending stress on the hinge, and the 95 other for convenience may be termed a compression force whereby the hooks are forced or pressed toward each other. When the cover is finally closed the bending moment is greatest and this gradually decreases as the cover opens returning the spring to normal position. When fully closed the compression force will not tend to open the box because the line of force is on the inside of the pivotal axis, but when moved slightly toward open position the compression force functions to continue the opening movement.

A cardinal feature of the invention consists in the spring arrangement and manner of attaching the spring to the hinge straps which enables the spring to be conveniently attached and detached. It will be under-

stood that in attaching the spring the hinge is opened to an angle corresponding to the angle of the spring and the hooked ends of the spring are slipped over the lips 11 thus 5 eliminating the trouble of initially flexing the spring before attaching.

Another important feature of the present invention resides in the novel manner of so anchoring the ends 12 of spring 13 between 10 the right-angle ends of leaf portions 3 and the hinge straps 6 and 7, that the ends of the spring are clamped in parallelism with the side portions of the box and cover respectively in all angular positions of the 15 cover. This not only holds the spring rigidly in place but produces a greater spring action, for a given sized spring, than in case the ends merely hooked over edges or through slots. By virtue of the right- 20 angle end of leaf portions 3 being disposed between the ends of the spring and the side portions of the box and cover respectively, the ends of the spring are prevented from gouging into or through said side portions 25 (which are ordinarily constructed of relatively non-resistant cardboard) during repeated opening and closing of the cover.

While the form of hinge shown and described is admirably adapted to fulfill the 30 objects primarily stated it is to be understood that it is not intended to confine the invention to the one embodiment herein disclosed, for it is susceptible of embodiment in various forms all coming within the scope 35 of the appended claims.

I claim:

1. A hinge for jewelry boxes and the like comprising a pair of pivoted hinge members, each member having a metal leaf portion fixed to the inner surface of the adjoining box ends, a hinge strap detachably connected to each of said leaf portions, means for pivotally connecting said hinge straps together, an outwardly projecting lip on the free edge of each of said straps and a unitary spring having hooked end portions engaging between said outwardly projecting portions and said leaf portions. 40

2. A hinge for jewelry boxes and the like comprising a pair of pivoted hinge members, each member having a base plate and a metal leaf portion extending substantially at right angles therefrom and secured to the inner surfaces of the adjoining box ends, a hinge strap detachably connected to each of said leaf portions, means for pivotally connecting said hinge straps together, an outwardly projecting lip in the free edge of each of said straps remote from said pivotal connection, the said free edges overlying said leaf portions distant from said base plates, and a unitary spring having hooked end portions of appreciable length clamped between said outwardly projecting portions and said leaf portions and lying flatwise 55 upon said leaf portions, whereby the position of said end portions is rigidly fixed. 60

Signed by me at North Attleboro, Massachusetts, this 21st day of November 1924.

RUSSELL I. RHODES.
